UNITED STATES PATENT OFFICE.

PERLEY C. BLAKE, OF HAVERHILL, MASSACHUSETTS, AND JOHN C. RINGE, OF STRATFORD, CONNECTICUT, ASSIGNORS TO THE SINGER MANUFACTURING COMPANY, OF ELIZABETH, NEW JERSEY, A CORPORATION OF NEW JERSEY.

SEWING MACHINE.

Application filed November 14, 1922. Serial No. 600,817.

To all whom it may concern:

Be it known that we, PERLEY C. BLAKE and JOHN C. RINGE, residing, respectively, at Haverhill, in the county of Essex and 5 State of Massachusetts, and at Stratford, in the county of Fairfield and State of Connecticut, have invented certain new and useful Improvements in Sewing Machines, of which the following is a specification, reference being had therein to the accompanying drawings.

This invention relates to improvements in edge-snipping mechanisms for sewing machines and has for its object to provide a 15 simplified construction of this character which is thoroughly efficient in operation and capable of being at will thrown into and out of operation.

In its preferred embodiment, the present 20 improved construction comprises a cutting-blade, disposed in a plane substantially transverse to the line of feed and carried by a pivotally supported lever yieldingly urged under the action of a spring into an inoperative 25 position determined by a suitable stop. Pivotally supported by this lever is a blade-actuating arm adapted to be thrown into and out of operative engagement with an eccentric carried by a shaft rotated at a speed 30 to impart a work-snipping movement to the cutting-blade for each two stitches formed. During the snipping operation, the actuating arm referred to rests upon the eccentric under the action of the lever throw-out 35 spring and in a position determined by a suitable stop collar defining a point of engagement beyond a vertical line containing the pivot-axis of the actuating arm, whereby there is no tendency for the arm to ride off 40 the eccentric during the snipping operation.

In order to, at will, throw the actuating arm into and out of operative engagement with the eccentric, there is provided a manually controlled shift-element having a cam-slot coacting with a stud projecting from the actuating arm to swing the latter laterally off the eccentric, a suitable stop limiting the throw-out movement of the arm. The shift-element is disposed to engage the blade-carrying lever to lift the same against the action of its spring, thereby permitting the arm to swing into its operative position upon

the eccentric. Should the arm fail to swing into this position upon said lifting of the lever, a wall of the cam-slot referred to engages the arm-stud to positively insure the operative position of the arm. 55

In the accompanying drawings, Fig. 1 is a sectional view in front side elevation of a sewing machine embodying the present 60 improvement. Fig. 2 is a rear side elevation of a portion of the same. Fig. 3 is an enlarged top-plan of the work-supporting arm of the sewing machine sectioned through the vertical standard thereof. Fig. 4 is a top-plan view of the front portion of the work-supporting arm. Fig. 5 is a sectional view substantially on the line $x-x$ of Fig. 4. Fig. 6 is a sectional view substantially on the line $y-y$ of Fig. 4. Fig. 7 is a view of a portion 70 of the work un-snipped. Fig. 8 is a top-plan view of the work showing both snipped and un-snipped portions thereof. Fig. 9 is a sectional view of the work after it is folded. 75

Referring to the drawings, the sewing machine illustrated is constructed substantially as fully shown and described in the patent to Albert Rontke, No. 989,538, dated April 11, 1911, and comprises a work-arm or cylinder 1, from which rises the hollow arm-standard 2 and overhanging bracket-arm 3 terminating in the head 4. Journaled in suitable bearings provided in the arm-standard and overhanging bracket-arm is the 80 main or needle-bar actuating shaft 5 carrying at one end the usual belt-pulley 6. The main-shaft 5 also carries the pulley 7, connected by means of the belt 8 with the pulley 9 secured upon the loop-taker actuating 90 shaft 10, suitably journaled in bearings provided in the work-cylinder 1 and carrying the loop-taker 11. 85

At its forward end, the main-shaft 5 carries the flange 12 in which is secured, by 95 means of the screw 13, the crank-stud 14 embraced by the sleeve 15 on one end of the link 16. The other end of the link 16 is provided with a sleeve 17 entered by the pin 18 projecting from the collar 19 suitably 100 secured upon the needle-bar 20, carrying the needle 21. By means of this construction, endwise reciprocatory movements are imparted to the needle-bar 20, which is jour-

naled in vertically alined apertures formed in the oscillating feed-frame 22. The loop-taker 11 which coacts with the needle 21 in the formation of lock-stitches, is rotated 5 twice for each reciprocation of the needle by virtue of the ratio of the pulleys 7 and 9.

The feed-frame 22 is mounted to oscillate upon pivotal bearings comprising the fulcrum-stud 23 threaded into the overhanging 10 arm and the stud 24, secured in the arm 25 of the feed-frame and journaled in a suitable aperture provided in the work-cylinder 1. To the forward end of the arm 25 of the feed-frame is secured the feed-bar 26 15 having the usual feed-dog 27 projecting upwardly through the aperture 28 provided in the throat-plate 29 suitably secured upon the work-cylinder 1. The feed-frame 22 receives its oscillating movements from an eccentric 20 30, on the main-shaft 5 and embraced by the strap 31 having the apertured boss 32 adapted to be entered by the pin 33. The pin 33 is formed or otherwise provided with an eccentric portion 34 which is adjustably 25 secured by means of the screw 35 in the apertured ear 36 provided on the feed-frame. The eccentric 30 may be adjusted to vary the feed by means of the rod 37 in a manner well known, and as fully shown and described in the patent to W. F. Dial et al., No. 30 718,988, January 27, 1903.

Projecting from the rear side of the work-cylinder 1 is a lug or supporting bracket 38 apertured for the reception of a headed 35 pivot-pin 39 secured in position by means of a set-screw 40. Journaled for oscillatory movements upon the pivot-pin 39 is the hub 41 of a lever 42 provided at its forward end with a head 43 upon which is adjustably 40 secured, by means of screws as 44, the slotted shank of a cutting-blade 45 having its cutting edge disposed in a plane substantially transverse to the line of feed. A spring 46 having one end secured to the machine head 4 and its other end to the lever 45 urges the forward end of the latter into a raised or inoperative position determined by a stop-screw 47 projecting above the work-supporting cylinder and disposed to 50 engage a boss 48 on the rear end of the lever 42. The boss 48 is apertured for the reception of a headed pivot-pin 49 secured in position by means of a set-screw 50. The pin 49 pivotally sustains an actuating arm 51 55 in its operative position disposed to ride the surface of an eccentric 52, having a flange 53 and secured upon a shaft 54 by means of a set-screw 55. At the side opposite to the flange 53, the eccentric 52 is 60 formed with an inclined arm-guiding surface 52', facilitating the movement of the arm into operative engagement with the eccentric. The shaft 54 is journaled at one end in a bushing 56 secured in a suitable 65 aperture in the bracket 38 by means of a

screw 57, the shaft being held against end-wise movement by means of a collar 58 at one side of the bushing and the eccentric 52 at the other side thereof. At its rearward end, the shaft 54 is journaled in an 70 apertured lug 59 provided on the machine frame, and adjacent said lug there is suitably secured upon the shaft 54 a spur-gear 60 meshing with a pinion 61 suitably fixed upon the loop-taker actuating shaft 10. The 75 relative proportions of the gearing 60, 61 are such that the shaft 54 is rotated once for two rotations of the main-shaft 5.

In order to at will throw the snipping blade into and out of operation there is 80 provided a manually controlled shift-element comprising an oscillatory cam-plate 62 rigidly carried by the end of a transverse rock-shaft 63 journaled in a bracket 64 upon the work-cylinder. Upon its front end, there is suitably secured upon the rock-shaft 63 a hand-lever 65 whereby the cam-plate 62 may be oscillated. The cam-plate 62 is provided with a notch or cam 66 entered by a stud 67 threaded into the arm 51 and is 85 also provided with a stop-pin 68 for limiting the throw-out position of said arm 51. By reference to Fig. 2 of the drawings, it will be observed that the point of engagement of the arm 51 with the eccentric 52 90 in the position determined by the flange 53 under the action of the spring 46 is beyond a vertical line through the pivotal axis of the arm 51. Consequently the tendency, 95 during the operation of the eccentric upon the arm 51, is to maintain the arm in engagement with the flange 53 thereby obviating the necessity of providing latches or other similar contrivances to hold the parts 100 in operative position.

Still referring to Fig. 2 of the drawings, when the hand-lever 65 is swung from the position indicated in a direction toward the blade 45, the wall 69 of the cam-notch 66 will engage the stud 67 and swing the arm 51 laterally off the eccentric into a position determined by the stop-pin 68. As soon as the arm 51 leaves the eccentric, the spring 46 is free to rock the lever 42 about its fulcrum to raise the blade 45 into an inoperative position determined by the stop-screw 47. Obviously the arm 51 cannot climb the inclined surface 52' of the eccentric 52 of its own accord against the action of the spring 46 and therefore no latches are required to lock the cutting blade in inoperative position. When the hand-lever 65 is manually swung in a direction away from the cutting-blade in the inoperative position of the latter, the edge 70 of the cam-plate 62 engages the boss 48 of the lever 42 and lifts the rearward end of the latter, thereby depressing the cutting blade 45 into operative position. The arm 51 in its inoperative position is laterally displaced 115 120 125 130

from a vertical position and therefore the action of lifting the rear end of the lever 42 permits the arm 51 to gravitationally seek its vertical position, thereby engaging 5 the operative face of the eccentric. Should the arm 51 however fail to perform this swinging movement, the wall 71 of the cam-notch 66 acts upon the stud 67 to insure such movement of the arm into its operative 10 position, which movement is facilitated by the inclined surface 52' of the eccentric.

Coacting with the movable cutting blade 45 is a stationary or ledger-blade 72 fixed upon the throat-plate 29 by means of screws 15 as 73. Dove-tailed into the throat-plate is a spring-pressed follower 74 which is under the action of a spring 75 secured upon the work-cylinder 1 to yieldingly close up the aperture in the throat-plate adjacent the 20 ledger-blade and to assist in maintaining the blades in shearing relationship. The position of the movable blade 45 with respect to the ledger-blade may be adjusted by means of the fastening screws 44 and a 25 set-screw 76 threaded into the head 43 and bearing against the blade. It will be observed that the edge of the follower 74 adjacent the ledger-blade is slightly inclined with respect to the latter to facilitate the 30 movement of the blade 45, while the usual aperture 77 is provided for the blade guide-finger.

While a sewing machine fitted with the present improved snipping mechanism is 35 adapted for effecting a large variety of products, it is particularly adapted for use in the production of a "French cord" edge in the manufacture of shoes. In Figs. 7, 40 8 and 9 of the accompanying drawings, there are illustrated several steps taken in one method of producing a "French cord" edge. A folded galloon *g* containing a cord *c* is directed to the needle 21 and under the feeding foot 78 and presser-foot 79 preferably by means of a suitable guide 80, for attachment to a shoe upper *m* by a line of 45 stitches *s* penetrating the galloon and the upper on a line closely adjacent to the cord and between the cord and the margins of 50 both materials, the margin of the shoe-upper being preferably skived as indicated. After the corded galloon has been attached to the upper, the margins are folded under as illustrated in Fig. 9 and suitably secured 55 in this position. It is evident that when sharp turns or curves occur in the work, some difficulty is encountered in smoothly folding the margins on account of the crimping of the materials. To this end it 60 is desirable to provide a plurality of transverse slits *b* in the margins at such turns or curves but omit the slitting operation at substantially straight portions of the work. The simple form of snipping mechanism 65 herein disclosed is admirably adapted for

this work and particularly by reason of ease of control of the movable knife for throwing it into and out of operation.

Having thus set forth the nature of the invention, what we claim herein is:—

1. An edge-snipping mechanism for sewing machines, comprising a cutting blade disposed in a plane substantially transverse to the line of feed, a blade carrying lever, a pivotal support for said lever, a blade 70 actuating arm pivotally sustained by said lever, a rotary eccentric for reciprocating said arm, means for relatively shifting said arm and eccentric into and out of effective operative relationship, and yielding means 75 for retracting said lever from operative position in the inoperative position of said arm.

2. An edge-snipping mechanism for sewing machines comprising a cutting blade, a blade-carrying lever, a pivotal support for said lever, yielding means tending to rock said lever to carry said blade into an inoperative position, an arm pivotally sustained by said lever, a rotary shaft, an 80 actuating eccentric carried by said shaft having an inclined arm-guiding surface at one side thereof, and means permitting shifting of the free end of said arm along the inclined surface of said eccentric to 85 operative position thereupon.

3. In a sewing machine, in combination, a cutting blade, a blade carrying lever, a pivotal support for said lever, a blade actuating arm pivotally sustained by said lever, a stop for determining the operative 100 position of said arm, a rotary shaft, an actuating eccentric carried by said shaft to reciprocate said arm, and yielding means for maintaining said arm in engagement 105 with said eccentric.

4. An edge-snipping mechanism for sewing machines, comprising a cutting blade disposed in a plane substantially transverse to the line of feed, a blade-carrying lever, a pivotal support for said lever, a spring urging said lever into an inoperative position, a stop for limiting the action of said spring in the inoperative position of said lever, an arm pivotally supported by said lever, a 110 blade-actuating element operating through said arm to limit the action of said spring in the operative position of said lever, and means for at will swinging said arm into an inoperative position.

5. An edge-snipping mechanism for sewing machines, comprising a cutting blade disposed in a plane substantially transverse to the line of feed, a blade carrying lever, a pivotal support for said lever, a rotary 115 blade-actuating element, a spring for yieldingly maintaining said lever in both operative and inoperative positions with respect to said actuating element, and a stop for limiting the action of said spring in the 120 inoperative position.

125

130

- operative position of said lever, said actuating element functioning as a stop to limit the action of the spring in the operative position of said lever.
- 5 6. An edge-snipping mechanism for sewing machines, comprising a cutting-blade disposed in a plane substantially transverse to the line of feed, a blade-carrying lever, a pivotal support for said lever, a spring urging said lever into an inoperative position, a blade-actuating arm pivotally sustained by said lever, a rotary eccentric for actuating said arm, and manually controlled means for swinging said arm out of operative engagement with said eccentric and permitting said spring to retract said blade out of operative position.
- 10 7. An edge-snipping mechanism for sewing machines, comprising a cutting blade, a blade-carrying lever, a pivotal support for said lever, a spring urging said lever into an inoperative position, a blade-actuating arm pivotally sustained by said lever, a rotary eccentric for actuating said arm, and a manually controlled shift element adapted to rock said lever from an inoperative to an operative position, said shift-element simultaneously insuring an operative engagement between said arm and said eccentric.
- 15 8. An edge-snipping mechanism for sewing machines, comprising a cutting blade, a blade-carrying lever, a pivotal support for said lever, a spring urging said lever into an inoperative position, a manually controlled shift-element for rocking said lever from an inoperative to an operative position, a rotary eccentric, a blade-actuating arm, a pivotal support for said arm disposed upon said lever to permit a lateral shift of said arm upon said eccentric when said lever is rocked from an inoperative to an operative position, and additional means carried by said shift-element for insuring the operative position of said arm.
- 20 9. An edge-snipping mechanism for sewing machines, comprising a cutting blade, a blade-carrying lever, a pivotal support for said lever, a spring yieldingly urging said lever into an operative position, a manually controlled shift-element for rocking said lever from an inoperative to an operative position, a rotary eccentric, a blade-actuating arm, a pivotal support for said arm disposed upon said lever to permit a lateral shift of said arm upon said eccentric when said lever is rocked from an inoperative to an operative position, means carried by said shift-element for insuring the operative position of said arm, and additional means on said shift-element for throwing said arm out of operative position.
- 25 10. An edge-snipping mechanism for sewing machines, comprising a cutting blade, a blade-carrying lever, a pivotal support for said lever, a spring yieldingly urging said lever into an inoperative position, a manually controlled shift-element for rocking said lever from an inoperative to an operative position, a rotary eccentric, a blade-actuating arm, a pivotal support for said arm disposed upon said lever to permit a lateral shift of said arm upon said eccentric when said lever is rocked from an inoperative to an operative position, means carried by said shift-element for insuring the operative position of said arm, and additional means on said shift-element for throwing said arm out of operative position, and means for limiting the throw-out movement of said arm.
- 30 11. An edge-snipping mechanism for sewing machines, including a cutting blade, a blade-carrying lever, a pivotal support for said lever, a rotary actuating element, an operative connection between said lever and said element comprising an arm pivotally supported by said lever and in operative position engaging said element at a point out of alignment with a vertical line passing through the pivotal axis of said arm, means for determining the operative position of said arm, and a spring acting upon said lever to yieldingly maintain said arm in its operative position.
- 35 12. An edge-snipping mechanism for sewing machines, including a cutting blade disposed in a plane substantially transverse to the line of feed, a pivotally supported blade-carrying lever, a rotary actuating element, an operative connection between said lever and said element, means for at will relatively shifting said connection and said element out of and into operative engagement during the operation of the machine, and a spring acting upon said lever to yieldingly hold the actuating parts therefor in both operative and inoperative positions.
- 40 In testimony whereof, we have signed our names to this specification.
